burgh, Pa., a corporation of Pennsylvania

Application December 14, 1946, Serial No. 716,197

12 Claims. (Cl. 172—281)

1

My invention relates to electronic frequency-changers or converters for converting directly from alternating current of one frequency to alternating current of a higher frequency. More particularly, my invention relates to high-frequency converters utilizing gas or vapor-filled tubes, whereby an output can be obtained, having a kilowatt rating which is greater than that which can be economically obtained with high-vacuum tubes.

An important field of application of the invention is in supplying energy for an induction furnace requiring frequencies in the range of from 1000 to 2000 cycles per second, more or less. This is a frequency-range in which rotating motor-generator sets have poor efficiency and poor regulating characteristics, and in which high-vacuum-tube oscillators can not be economically used.

The principal object of my present invention is to provide power-circuits for high-frequency electronic converters of the type which I have described, in which two groups of tubes are provided, each group having its anode-circuits connected to the several phases or conductors of the input-circuit, and having a separate cathode-bus, in combination with an output-transformer or reactor having a mid-tapped primary winding, the midpoint of which is connected, preferably through a reactor, to the neutral point or intermediate-voltage point of a power-transformer which is utilized in the input-circuit. The load or high-frequency output-circuit is connected to the output-transformer.

A more particular object of my invention is to provide a commutating-capacitor, preferably shunt-connected across the primary terminals of the output-transformer, in a combination such as I have described.

By means of my present invention, I have been able to achieve success, in a high-frequency electronic converting apparatus, where other power-circuits have proved unsuitable.

My present invention is applicable to gas-filled hot-cathode tubes, or to ignitrons. Suitable gas-filled hot-cathode tubes, in my high-frequency converter, will make it possible to obtain efficient operation in a frequency-range extending up to 3000 cycles, or more, in installations in which the power-requirements are not too high. Special ignitrons, in my high-frequency converter, will have a greater output-capacity, but in general can not, at present, be operated at frequencies exceeding 1500 or 2000 cycles.

When my present invention is applied to ig-

2

nitrons, it is preferably to utilize a special excitation-control circuit which constitutes the subject-matter of my concurrently filed copending application Serial No. 716,196, filed December 14, 1946, although I am not altogether limited, in the present invention, to any particular excitation-control.

With the foregoing and other objects in view, my invention consists in the circuits, systems, methods, combinations and parts, hereinafter described and claimed, and illustrated in the accompanying drawings, wherein Figures 1 and 2 are simplified diagrammatic views illustrating the essential features of two different forms of embodiment of my invention, omitting known features of switches, voltage-regulators, and other like features which are not necessary to an understanding of the present invention.

In Figure 1, I show the fundamental features of the power-circuits and the excitation-circuits of a preferred form of embodiment of my invention, utilizing six ignitron-tubes, 1 through 6, which are supplied from a three-phase input-circuit 7 which is energized from a commercial-frequency power-transformer 8, having delta-connected primary windings 9, and zig-zag secondary windings 10 having a neutral point 11. The primary windings 9 are energized from a three-phase circuit 13, of 60 cycles or other frequency. The secondary windings 10 energize the three-phase input-circuit 7 of the ignitrons 1 to 6.

The ignitrons are disposed in two groups, 1, 2 and 3, and 4, 5 and 6, respectively. Each phase of the input-circuit 7 is connected to the anode-circuits 14 of two ignitrons, one in each group. The three cathode-circuits 15 of the tubes 1, 2 and 3, in the first group, are connected to a common cathode-bus 16; while the three cathode-circuits 15 of the tubes 4, 5 and 6, of the other group, are connected to another common cathode-bus 17.

In accordance with my present invention, a high-frequency load-circuit is connected to the two cathode-buses 16 and 17, by means of an output-transformer or reactor 20 having a mid-tapped primary winding 21, the mid-point 22 of which is connected to the neutral point 11 of the secondary winding 10 of the power-supply transformer 8, preferably through a direct-current reactor 23, which reduces the circulation of the high-frequency fundamental and harmonic currents in the supply-transformer 8, and also helps to reduce any pulsation in the high-frequency output-voltage wave.

The output-circuit 24 of the converter is shown

as being energized from a secondary winding 25 of the output-transformer 20, and it is shown as being connected to an induction furnace 26 which is symbolically represented by an inductance 27 and a resistance 28.

In most cases, it will be necessary to utilize a commutating-capacitor 30, for effecting the high-frequency commutation of the output-currents of the converter, or for at least assisting in the commutation of such currents. As shown in Fig. 1, the commutating-capacitor 30 is connected across the two cathode-buses 16 and 17, that is, across the primary terminals of the output-transformer 20. A second capacitor 31, for power-factor-correction purposes, is also commonly connected across the terminals of the induction-furnace load 26, that is, across the secondary terminals of the output-transformer 20.

It is possible, of course, to omit either one of the capacitors 30 or 31, and to utilize the remaining capacitor to take over the functions of both, increasing the size of the remaining capacitor, for this purpose. It is usually more economical, however, to utilize the capacitor 31 to adjust the power-factor of the load to near unity, and to utilize the capacitor 30 solely for commutating purposes, for alternately charging, first in one direction and then the other, during successive half-cycles of the output-frequency, cutting off the output-current at the end of each output-frequency half-cycle, thus extinguishing, or commutating, the load-currents flowing through the main anode-cathode circuits of the several tubes 1 to 6, according to whichever tube is carrying current at the moment.

As more particularly described and claimed in my copending application, a special excitation-circuit is utilized for the converter-tubes 1 to 6.

Each tube, in addition to its anode-circuit 14 and cathode-circuit 15, is provided with a control or shielded grid 33, in closely spaced relation with respect to the anode, an excitation grid 34 in closely spaced relation to the control grid, an ignitor 35, and an auxiliary anode or electrode 36. A tiny circle or dot 37 has been placed within the diagrammatic representation of each tube, as a convention for indicating the presence of a gas or vapor, or other means for causing the ignitor or other control-electrode of the tube to become ineffective, in general, to stop the firing of the tube, once the firing has been initiated. The outer grid 34 acts as a deionizing surface for the inner control grid 33. The spacings between the inner grid and the anode, and between the two grids, should be as small as is mechanically possible, usually about one-quarter of an inch. The grids should be thin, with small holes therein, usually about one-eighth to one-quarter of an inch in diameter. By these expedients, the grids are made more effective to control the tubes at a high-frequency rate.

The exciting currents for the several ignitors 35, of the tubes 1 to 6, are supplied by a set of three single-phase firing-circuit excitation-transformers 40, and six ignitor-coupling insulating-transformers 41.

As more particularly described and claimed in my copending application, the number of ignitor-misfires may be reduced, by connecting the ignitor-coupling transformers 41 in series in pairs, so as to fire the two ignitors which should fire at the same time. The series connection has the advantage that, when one of the two ignitors does not fire as soon as the other, a double voltage is impressed upon the hard-firing ignitor.

The series ignitor-firing effect can be obtained in a number of different ways, as by means of a mid-tapped balancing-coil 42 which is connected between each secondary winding of the excitation-transformer 40 and the two coupling-transformers 41 which energize the two ignitors 35 which are to be excited by that winding of the excitation-transformer.

The primary windings of the excitation-transformers 40 are energized from an auxiliary three-phase bus 43, which is energized from the secondary windings of an auxiliary transformer 44, the primary windings of which are connected to the main power-circuit 13.

15 The firing-points, in the input-frequency cycles, are advanced or retarded by means of variably saturable reactors 45, which are connected in series with each of the three secondary windings of the excitation-transformer 40, the saturation of these reactors being controllable by means of a direct-current saturating-coil 46, which is excited from a battery 47 through a controllable rheostat 48.

20 During each firing half-cycle, the voltage delivered by the secondary winding of the excitation-transformer 40 is built up upon an energy-storing capacitor 49, which is connected in shunt across the firing-excitation circuit. To obtain a valve-action, a fixed saturating reactor 50 is serially connected between the capacitor 49 and the two ignitor-coupling transformers 41 which are served from that circuit. At a predetermined point in the half-cycle, this saturating reactor 50 becomes saturated, thus suddenly losing its impedance, and permitting a heavy current-impulse to be discharged from the capacitor 49 into the ignitor-coupling transformers 41.

25 The secondary winding of each ignitor-coupling transformer 41 delivers only the positive peaks 30 of its current to the ignitor 35 of the associated one of the main tubes 1 to 6, this action being accomplished by means of a serially connected rectifier 51. A return-path for the flux-decay current of the coupling-transformer 41 is provided in a known manner by means of a rectifier 52 which is connected across the transformer-secondary.

35 Since my converter is converting from a relatively low frequency to a relatively high frequency, each low-frequency conducting-period, of each tube, must be broken up into a plurality of conducting and non-conducting periods, at the high-frequency rate.

40 As more particularly described and claimed in my copending application, the grids 33 and 34, of each of the converter-tubes 1 to 6, are utilized to alternately block and release the firing of the several tubes, at the output-frequency rate. The two grids 33 and 34 of each tube are energized together, from the same high-frequency source, through separate, serially connected resistors 53 and 54, so that the two grids can assume different potentials according to the amount of grid-current, which they respectively draw. 45 Any suitable high-frequency source may be utilized, for energizing the grids 33 and 34, at the desired output-frequency. By way of illustration, an oscillation-generator 55 is shown, which is, or may be, of a conventional and well-understood type, so that no detailed description thereof is needed. The oscillation-generator 55 has two output-windings 56 and 57, which are utilized to provide two output-frequency circuits of opposite potentials, one being positive while the other 50 is negative.

The grid-control circuits also include negative biasing-batteries 58 and 59 respectively, one biasing-battery 58 being for one group of converter tubes, 1, 2 and 3, while the other biasing-battery 59 is for the other group 4, 5 and 6. Since each of the two groups of converter-tubes has its own cathode-circuit 16 or 17, which is common to all of the tubes of that group, the grids 33 and 34 of all of the tubes of each group can be energized from the same high-frequency source. Thus, the grids of the tubes 1, 2 and 3 are energized from the high-frequency output-winding 56, in series with the negative biasing-battery 58; while the grids of the tubes 4, 5 and 6 are energized from the high-frequency output-winding 57, in series with the negative biasing-battery 59. In an illustrative case, a negative bias of about 100 volts has been found advisable, for the batteries 58 and 59, in combination with a peak oscillator-voltage of about 200 volts, on each of the oscillator output-windings 56 and 57, although it is to be understood that I am not limited to any particular voltages.

Since the ignitor 35 of each of the converter-tubes is energized only once during each input-frequency cycle, and since the period during which an energizing current flows in the ignitor is only a brief portion of the input-frequency cycle, it will be obvious that the length of the portion of the input-frequency cycle during which any converter-tube could be fired, by the control-action of the grids, at the high-frequency rate, would be limited to the same brief portion of the low-frequency cycle as the duration of the flow of effective ignitor-current, if suitable means were not provided. I therefore utilize an auxiliary anode 36, in each tube; but contrary to ordinary practice, I usually or frequently find it desirable to provide for a wide phase-shift adjustment of the firing-angle, as by means of the rheostat 43. To make this possible, as described and claimed in my copending application, I so excite the auxiliary anode 36, in Fig. 1, as to maintain a strong holding-arc thereon for 120 input-frequency degrees, plus the input-frequency commutating-angle of the tubes, which may be another 10 or 20 degrees, more or less.

Thus, in Fig. 1, the auxiliary electrodes 36 of the six converter-tubes 1 to 6 are energized from a set of single-phase holding-circuit transformers 60. The three primary windings of the holding circuit transformers are energized from the auxiliary three-phase input-frequency bus 43. Each of the three holding-circuit transformers 60 has a plurality of secondary windings; and these secondary windings are illustrated as being connected in two zig-zag winding-connections 64 and 65, having neutral points 66 and 67, which are connected to the respective cathode-buses 16 and 17. The several phase-terminals of the zig-zag winding 64 are utilized to energize the auxiliary anodes 36 of the converter-tubes 1, 2 and 3, through separate current-limiting resistors 68, while the several phase-terminals of the zig-zag winding 65 are utilized to energize the auxiliary anodes 36 of the converter-tubes 4, 5 and 6, each through its own resistor 68.

In order to obtain an auxiliary-anode energization-period of 120 input-frequency degrees, or more, for each of the converter-tubes 1 to 6, each tube has its auxiliary-anode 36 energized, not only from the usual phase-circuit, or terminal, of the holding-circuit transformer 60, but also, in parallel therewith, from the next lagging phase-circuit, as shown, for example, at 69. The

auxiliary-anode energization-circuits include rectifiers 70, which are connected, in each circuit, in series with each of the phase-terminals of the secondary windings 64 and 65, so as to avoid short-circuiting the parallel-connected windings, while at the same time delivering only the positive impulses of current from the respective windings.

In the operation of the converting apparatus 10 which is shown in Fig. 1, it may be noted that, although the main converter-tubes 1 to 6 are of a type in which neither the two grids 33 and 34 together, nor the ignitor 35, nor the auxiliary anode 36, is capable, in general, of interrupting the flow of a main-circuit current in any tube, once the tube has been fired by establishing an arc between the main anode and the cathode, within the tube, nevertheless a load-circuit is provided, which is of such character as to be 15 able to effect a periodic interruption of the tube-current, or of the main arc within the tube, at the output-frequency rate. In the circuit which is shown in Fig. 1, this current-interrupting or 20 commutating function is performed principally by 25 the parallel-connected capacitor 30.

In the control-circuits, it is to be noted that 30 each of the main converter-tubes 1 to 6 is fired once, during each input-frequency cycle, by the energization of its ignitor-circuit. When the ignitor 35 of any tube establishes a firing-arc, the auxiliary anode 36 of that tube practically instantly fires, and picks up a holding arc, which is maintained for 120 input-frequency degrees, plus the input-frequency commutating-time of 35 the tubes, or for any other desired or necessary length of time. The commutating-time of the tubes is the time necessary to transfer the main arc from one input-phase to another, and this 40 commutating time can be shortened by utilizing a main transformer 8 which has a low reactance, and by other means.

While the grids 33 and 34 can not, in general, 45 interrupt the main arc in their tube, once said main arc has been established, they can prevent the establishment of the main arc, if the grids are sufficiently negative with respect to the cathode of the tube, or if the control-grid 33 has a potential which is more negative than a certain critical potential. It is to be noted that the 50 grids 33 and 34 of each tube are governed by a combination of a negative bias and a single-phase high-frequency voltage, so that, during a portion of each high-frequency cycle, the grids are sufficiently negative to block the firing or 55 initiation of the main arc in the tube, after which the grids become sufficiently positive, at a predetermined point in each high-frequency cycle, to permit the firing of the tube, provided that an exciting-arc is being carried, either by the 60 ignitor 35 or by the auxiliary electrode 36, and provided, also, that the main anode of the tube is sufficiently positive with respect to the tube-cathode, at the moment.

It is to be noted that the grids of the tubes 65 of one group of converter-tubes, namely the tubes 1, 2 and 3, become sufficiently positive, so as to "release" the respective tubes, for firing, during positive half-cycles of the output-frequency, while the grids of the tubes of the other group, 4, 5 and 6, "release" their tubes during the negative half-cycles of the output-frequency. Thus, one or more tubes of one group is carrying current during one half-cycle of the output-frequency, while none of the tubes of the other group are carrying current, the circuit being completed

through the direct-current connection 22-23. The zig-zag connection of the main-transformer secondaries 10 prevents this direct current from saturating the transformer.

During the next high-frequency half-cycle, the first group of tubes is non-conducting, while the second tube-group is conducting current.

During this interchange, when power is being supplied alternately by the cathode-bus 16 and by the cathode-bus 17, at the high-frequency rate, 10 the parallel-connected capacitor 30 is alternately charging and discharging, first in one direction and then in the other, cooperating with the direct-current return-circuit path 22-23, to also provide a return-path for whichever tube-group is carrying current at the moment, while also performing the function of interrupting the high-frequency current when the other tube-group is released, during any half-cycle of the high or output-frequency.

Fig. 2 shows a modification of the power-circuit in which a six-phase converter-operation is utilized. I utilize a six-phase supply, obtained from the star-connected six-phase secondary-winding 71 of a power-transformer 72, having a three-phase delta-connected primary winding 73 which is energized from the three-phase commercial-frequency power-line 13.

There are twelve tubes T1 to T12, comprising two groups having the separate cathode-buses 16 and 17. The tubes T1 to T6 constitute the first group, having their anode-leads 14 connected to the respective phases of the six-phase supply-transformer winding 71. The tubes T7 to T12 constitute the second group, having their anode-circuits 14 also connected to the respective phases of the six-phase secondary winding 71. Thus, one secondary terminal is connected to the anode-circuits 14 of the tubes T1 and T7 of the first and second groups, respectively. The next lagging transformer-phase is connected to the anode-circuits 14 of the tubes T2 and T8, respectively, and so on. All of the cathode-circuits 15 of the tubes T1 to T6 of the first group are connected to the cathode-bus 16, while all of the cathode-circuits 15 of the tubes T7 to T12 are connected to the cathode-bus 17.

The load-circuit, in Fig. 2, is connected to the two cathode-buses 16 and 17, respectively, the same as in Fig. 1, except that the primary-side load-circuit capacitor 30 of Fig. 1 has been omitted in Fig. 2, by way of illustration of the fact that its function can be taken over by utilizing a larger secondary-circuit capacitor 31 in parallel with the load.

The control-circuits in Fig. 2 are essentially the same as in Fig. 1, so that no further explanation is considered necessary, except to note that, in Fig. 2, the six insulating-transformers 41, which energize the ignitors, are physically connected in series, in pairs, to the secondary windings of the three excitation-transformers 40, instead of utilizing the balancing-reactors 42 of Fig. 1. In Fig. 2, since there are twelve converter-tubes, connected in two six-phase groups, instead of six tubes, connected in two three-phase groups, as in Fig. 1, the secondary windings of the ignitor-coupling insulating-transformers 41, and also the secondary windings of the holding-circuit transformers 60, are mid-tapped windings, each serving two diametrically opposite ignitors or auxiliary anodes, as the case may be, as will be readily understood.

In Fig. 2, also, the holding-circuits are arranged so that each auxiliary anode is energized

from only one phase of the holding-circuit transformers 60, and the holding-circuit rectifiers 63 of Fig. 1 have been omitted as being therefore unnecessary. This produces a holding-circuit, in Fig. 2, which will not remain energized as long as the holding-circuit in Fig. 1, which means that the system of Fig. 2 will not be susceptible of as wide a range of voltage-regulation, by manipulation of the saturating-reactor rheostat 48, as is possible in Fig. 1. The particular application for which Fig. 2 was designed did not require the additional range of voltage-regulation.

While I have illustrated my invention in two different forms of embodiment, and while I have described the same in accordance with my best present understanding, I wish it to be understood that I am not limited to the illustrated embodiments or to the explanations which I have given. I desire, therefore, that the appended claims shall be accorded the broadest construction consistent with their language.

I claim as my invention:

1. In combination, an alternating-current supply-circuit winding having a neutral point; means for providing an alternating-current output-circuit, the output-circuit having a frequency higher than the supply-circuit; a multi-tube electronic converter between said supply-circuit winding and said output-circuit, said converter having two groups of tubes, each group having a separate cathode-circuit output-bus; a mid-tapped output-transformer winding connected across the two cathode-buses; and means for connecting the midpoint of the output-transformer to the neutral of the supply-circuit winding.

2. In combination, means for providing a supply-circuit having a neutral point; means for providing a high-frequency output-circuit; a multi-tube electronic converter between said supply-circuit and said output-circuit, each tube of the converter having a main anode-cathode circuit, and control-electrode means; said control-electrode means being, in general, incapable of interrupting the current in the main anode-cathode circuit of the tube, once said tube has been fired; said converter comprising control-means for so energizing the control-electrode means of each tube as to intermittently block and unblock the firing, at the output-frequency rate; said converter having two groups of tubes, each group having a separate cathode-circuit output-bus, the output-frequency controls of the two tube-groups being in phase-opposition; a mid-tapped output-transformer winding connected across the two cathode-buses; and means for connecting the midpoint of the output-transformer to the neutral of the supply-circuit.

3. In combination, an alternating-current supply-circuit winding having a neutral point; means for providing an alternating-current output-circuit, the output-circuit having a frequency higher than the supply-circuit; a multi-tube electronic converter between said supply-circuit winding and said output-circuit; each tube of the converter having a main anode-cathode circuit, and control-electrode means; said control-electrode means being, in general, incapable of interrupting the current in the main anode-cathode circuit of the tube, once said tube has been fired; said converter comprising control-means for so energizing the control-electrode means of each tube as to continuously tend to fire the tube during a considerable portion of each positive half-cycle of the input-power, and to intermittently block and unblock such firing at the output-fre-

quency rate; said converter having two groups of tubes, each group having a separate cathode-circuit output bus, the output-frequency controls of the two tube-groups being in phase-opposition; a mid-tapped output-transformer winding connected across the two cathode-buses; and means for connecting the midpoint of the output-transformer to the neutral of the supply-circuit winding.

4. In combination, an alternating-current supply-circuit winding having a neutral point; means for providing an alternating-current output-circuit, the output-circuit having a frequency higher than the supply-circuit; a multi-ignitron converter therebetween, each ignitron of the converter having a main anode-cathode circuit, an ignitor, an auxiliary anode, and grid-means; said converter comprising a control-means for each ignitron, including means for exciting the ignitor at the input-frequency, means for exciting the auxiliary anode so as to thereafter maintain a holding-arc for a considerable portion of an input-frequency cycle, and means for controlling the grid-means so as to alternately block and permit the firing of the ignitron on alternate half-cycles of the output-frequency; said converter having two groups of ignitrons, each group having a separate cathode-circuit output-bus, the output-frequency controls of the two ignitron-groups being in phase-opposition; a mid-tapped output-transformer winding connected across the two cathode-buses; and means for connecting the midpoint of the output-transformer to the neutral of the supply-circuit winding.

5. In combination, an alternating-current supply-circuit winding having a neutral point; means for providing an alternating-current output-circuit, the output-circuit having a frequency higher than the supply-circuit; a multi-tube electronic converter between said supply-circuit winding and said output-circuit, said converter having two groups of tubes, each group having a separate cathode-circuit output-bus; a mid-tapped output-transformer winding connected across the two cathode-buses; means for connecting the midpoint of the output-transformer to the neutral of the supply-circuit winding, and a commutating-capacitor means, associated with the output-circuit, for materially assisting in commutating the successive half-cycles of the output-current.

6. In combination, means for providing a supply-circuit having a neutral point; means for providing a high-frequency output-circuit; a multi-tube electronic converter between said supply-circuit and said output-circuit, each tube of the converter having a main anode-cathode circuit, and control-electrode means, said control-electrode means being, in general, incapable of interrupting the current in the main anode-cathode circuit of the tube, once said tube has been fired; said converter comprising control-means for so energizing the control-electrode means of each tube as to intermittently block and unblock the firing, at the output-frequency rate; said converter having two groups of tubes, each group having a separate cathode-circuit output-bus, the output-frequency controls of the two tube-groups being in phase-opposition; a mid-tapped output transformer winding connected across the two cathode-buses; means for connecting the midpoint of the output-transformer to the neutral of the supply-circuit, and a commutating-capacitor means, associated with the output-circuit, for materially assisting in com-

mutating the successive half-cycles of the output-current.

7. In combination, an alternating-current supply-circuit winding having a neutral point; means for providing an alternating-current output-circuit, the output-circuit having a frequency higher than the supply-circuit; a multi-tube electronic converter between said supply-circuit winding and said output-circuit, each tube of the converter having a main anode-cathode circuit, and control-electrode means, said control-electrode means being, in general, incapable of interrupting the current in the main anode-cathode circuit of the tube, once said tube has been fired; said converter comprising control-means for so energizing the control-electrode means of each tube as to continuously tend to fire the tube during a considerable portion of each positive half-cycle of the input-power, and to intermittently block and unblock such firing at the output-frequency rate; said converter having two groups of tubes, each group having a separate cathode-circuit output-bus, the output-frequency controls of the two tube-groups being in phase-opposition; a mid-tapped output-transformer winding connected across the two cathode-buses; means for connecting the midpoint of the output-transformer to the neutral of the supply-circuit winding, and a commutating-capacitor means, associated with the output-circuit, for materially assisting in commutating the successive half-cycles of the output-current.

8. In combination, an alternating-current supply-circuit winding having a neutral point; means for providing an alternating-current output-circuit, the output-circuit having a frequency higher than the supply-circuit; a multi-ignitron converter therebetween, each ignitron of the converter having a main anode-cathode circuit, an ignitor, an auxiliary anode, and grid-means; said converter comprising a control-means for each ignitron, including means for exciting the ignitor at the input-frequency, means for exciting the auxiliary anode so as to thereafter maintain a holding-arc for a considerable portion of an input-frequency cycle, and means for controlling the grid-means so as to alternately block and permit the firing of the ignitron on alternate half-cycles of the output-frequency; said converter having two groups of ignitrons, each group having a separate cathode-circuit output-bus, the output-frequency controls of the two ignitron-groups being in phase-opposition; a mid-tapped output-transformer winding connected across the two cathode-buses; means for connecting the midpoint of the output transformer to the neutral of the supply-circuit winding, and a commutating-capacitor means, associated with the output-circuit, for materially assisting in commutating the successive half-cycles of the output-current.

9. In combination, an alternating-current supply-circuit winding having a neutral point; means for providing an alternating-current output-circuit, the output-circuit having a frequency higher than the supply-circuit; a multi-tube electronic converter between said supply-circuit winding and said output-circuit, said converter having two groups of tubes, each group having a separate cathode-circuit output-bus; a mid-tapped output-transformer winding connected across the two cathode-buses; means for connecting the midpoint of the output-transformer to the neutral of the supply-circuit winding, a commutating capacitor, connected in parallel-

circuit relation to said output-transformer winding, for materially assisting in commutating the successive half-cycles of the output-current.

10. In combination, means for providing a supply-circuit having a neutral point; means for providing a high-frequency output-circuit; a multi-tube electronic converter between said supply-circuit and said output-circuit, each tube of the converter having a main anode-cathode circuit, and control-electrode means, said control-electrode means being, in general, incapable of interrupting the current in the main anode-cathode circuit of the tube, once said tube has been fired; said converter comprising control-means for so energizing the control-electrode means of each tube as to intermittently block and unblock the firing, at the output-frequency rate; said converter having two groups of tubes, each group having a separate cathode-circuit output-bus, the output-frequency controls of the two tube-groups being in phase-opposition; a mid-tapped output-transformer winding connected across the two cathode-buses; means for connecting the midpoint of the output-transformer to the neutral of the supply-circuit, a commutating-capacitor, connected in parallel-circuit relation to said output-transformer winding, for materially assisting in commutating the successive half-cycles of the output-current.

11. In combination, an alternating-current supply-circuit winding having a neutral point; means for providing an alternating-current output-circuit, the output-circuit having a frequency higher than the supply-circuit; a multi-tube electronic converter between said supply-circuit winding and said output-circuit, each tube of the converter having a main anode-cathode circuit, and control-electrode means, said control-electrode means being, in general, incapable of interrupting the current in the main anode-cathode circuit of the tube, once said tube has been fired; said converter comprising control-means for so energizing the control-electrode means of each tube as to continuously tend to fire the tube during a considerable portion of

each positive half-cycle of the input-power, and to intermittently block and unblock such firing at the output-frequency rate; said converter having two groups of tubes, each group having a separate cathode-circuit output-bus, the output-frequency controls of the two tube-groups being in phase-opposition; a mid-tapped output-transformer winding connected across the two cathode-buses; means for connecting the midpoint of the output-transformer to the neutral of the supply-circuit winding, a commutating capacitor, connected in parallel-circuit relation to said output-transformer winding, for materially assisting in commutating the successive half-cycles of the output-current.

12. In combination, an alternating-current supply-circuit winding having a neutral point; means for providing an alternating-current output-circuit, the output-circuit having a frequency higher than the supply-circuit; a multi-ignitron converter therebetween, each ignitron of the converter having a main anode-cathode circuit, an ignitor, an auxiliary anode, and grid-means; said converter comprising a control-means for each ignitron, including means for exciting the ignitor at the input-frequency, means for exciting the auxiliary anode so as to thereafter maintain a holding-arc for a considerable portion of an input-frequency cycle; and means for controlling the grid-means so as to alternately block and permit the firing of the ignitron on alternate half-cycles of the output-frequency; said converter having two groups of ignitrons, each group having a separate cathode-circuit output-bus, the output-frequency controls of the two ignitron-groups being in phase-opposition; a mid-tapped output-transformer winding connected across the two cathode-buses; a means for connecting the midpoint of the output-transformer to the neutral of the supply-circuit winding; a commutating-capacitor, connected in parallel-circuit relation to said output-transformer winding, for materially assisting in commutating the successive half-cycles of the output current.

JOHN L. BOYER.
